MASSAGER

Joseph A. La Barber, 1313 Maenpah Circle,
Las Vegas, Nev.

Filed Nov. 15, 1965, Ser. No. 88,113

Term of patent 14 years

(Cl. D83—1)

FIG. 1

FIG. 2

FIG. 3

FIG. 4

FIGURE 1 is a side elevation view of a massager showing my new design. The opposite side is identical.

I claim:

The ornamental design for a massager, as shown and described.
